UNITED STATES PATENT OFFICE.

FRANKLIN L. LANE, OF BELOIT, WISCONSIN, ASSIGNOR TO P. B. YATES MACHINE COMPANY, OF BELOIT, WISCONSIN, A CORPORATION OF WISCONSIN.

CHIP BREAKER.

1,402,938.

Specification of Letters Patent: Patented Jan. 10, 1922.

Application filed March 7, 1921. Serial No. 450,313.

To all whom it may concern:

Be it known that I, FRANKLIN L. LANE, a citizen of the United States, residing at Beloit, in the county of Rock and State of 5 Wisconsin, have invented certain new and useful Improvements in Chip Breakers, of which the following is a specification.

My invention relates to the so-called chip-breakers of wood-working machines which 10 act as pressure bars bearing on the lumber undergoing a planing operation and which constitute means for breaking off the chips close to the planing knives or cutters thus rendering possible the production of a 15 smooth finished surface.

One prime object of the present invention is the provision of a construction of this 20 general character which will exert a substantially equal pressure on boards of different thicknesses within the capacity of the machine.

In other words, one salient characteristic of this invention is the prevention of an increase of such pressure when thicker boards 25 are passing through the machine.

To this end, the mounting for the chip-breaker is supplied with a spring construction, the effective action of which on the chip-breaker decreases as the thickness of 30 the work increases, thereby compensating for or neutralizing the increase of pressure of the chip-breaker on the work occasioned by the drag of the former on the latter and by reason of the different disposition of the 35 parts of the chip-breaker structure when acting on thicker boards.

In the accompanying drawing, I have 40 illustrated very simply a convenient and desirable embodiment of the invention which will be understood both from construction and functional aspects by those skilled in the art from the following detailed description of its structural characteristics and its mode of functioning.

45 As is depicted in a somewhat simplified or diagrammatical manner, the appliance includes the usual flat, horizontal bed-plate 10 over which the board or other piece of lumber 11 is fed in the customary manner by upper 50 and lower feed-rollers 12 and 13 driven by power in the ordinary and regular way, the planing operation being performed by the common or familiar planing cylinder 14 equipped with suitable knives or cutters.

The chip-breaker comprises an angular or 55 bent body 15 with outstanding flanges 16, of which only one is illustrated, and it has a chilled shoe or foot 17 secured in any approved manner on its lower end, such shoe having a bottom rounded or beveled face 60 adapted to ride on the upper surface of the work.

The top end of such chip-breaker is pivotally connected at 18 to one end of one arm 19 of a lever fulcrumed in any suitable manner at 20 between parallel, outwardly-extended flanges 21 of a stationary hollow, cross or transverse supporting bar 22.

At its lower portion, the chip-breaker is carried by a link 23, preferably of the same 70 length as the lever arm 19 to afford a parallel-motion construction, such link being pivoted at one end at 24 to the flanges or ribs of the chip-breaker and at the other end at 25 to depending portions of the flanges 75 21 of the support 22.

Such link and lever normally occupy a somewhat inclined or sloping position, the descent of the chip-breaker and its shoe being limited or restricted by an adjustable 80 stop or abutment screw 100 extended through the lever arm 19 and positioned to engage the top of the hollow cross bar 22 when no lumber is beneath the chip-breaker, thus facilitating the introduction of the 85 next board.

In order to supplement the action of the weight of the chip-breaker on the work, a suitable spring construction is provided comprising an eye-bolt 26 hinged to the 90 short arm 27 of the top lever at 28; that is to say, this pivotal connection is on the opposite side of the fulcrum 20 from the chip-breaker, so that any upward pressure on the eye-bolt results in a downward thrust on 95 the chip-breaker.

Conveniently, the lever arm 27 is formed of two, spaced parts or ears integral with the lever arm 19 and accommodating the head of the eye-bolt between them, the 100 hinge-pin 28 being fast in the eye of the bolt and adapted to turn in bearings in the arms 27.

The shank of such eye-bolt fits in and is adapted to slide in a tubular guide 29 positioned over the cylindrical stem 30 of a spring hinge element 31 fulcrumed between spaced ears 32 of the link 23 on a pin 33.

The screw threaded part of the eye-bolt is equipped with an adjustable abutment nut 34 and an associated lock-nut 35, and between the former and pressing against it 5 and the head of the spring-hinge member 31 and bearing against the latter is a coil spring 36 normally under compression and encircling or enclosing the guide 29 and the threaded shank of the eye-bolt.

10 The upward pressure of the top end of the spring on the lever 27—19 to the right of its fulcrum through the co-operating elements 34, 26 and 28 and the downward thrust of the other end of the spring on the 15 link to the left of its pivotal connection with the stationary support through the co-acting members 31 and 33 act to force the chip-breaker down on to the top surface of the lumber passing through the machine, 20 this action being supplemented by the downward pressure of the chip-breaker due to its own weight.

It will also be understood that the frictional engagement or the drag of the top 25 surface of the rapidly traveling piece of lumber on the lower face of the chip-breaker shoe tends in some degree to carry the shoe with it to the left as the parts are viewed in the drawing, and, consequently, tends to 30 rock the supporting lever and link counter-clockwise around their pivotal connections with the stationary support.

Obviously, the thicker the lumber the greater the downward turning movement on 35 the link and lever and the greater the pressure of the foot or shoe on the lumber caused by the travel of the latter and the frictional contact of the one with the other.

If, therefore, no means were employed to 40 counteract or neutralize such pressure increase of the shoe on the lumber, the thicker the latter the greater the pressure the shoe would impose thereon.

This is an undesirable condition and accordingly the spring construction is supplied to avoid it.

It will be perceived that as the thickness of the lumber acted upon increases, the axis of the coil spring approaches the axes of 50 the fulcrums of the lever and link, and consequently the expansive pressure of the spring is less efficiently applied to these two chip-breaker supporting elements.

It will be noted that the lever 19—27 is 55 not straight but has a more or less substantial bend at its fulcrum.

By so choosing such angle, the strength and adjustment of the spring, and its points of attachment to the lever and link, the 60 chip-breaker may be caused to exert substantially the same pressure on all thicknesses of the work within the range or capacity of the machine.

In any case, it is desirable to so select 65 these factors that the chip-breaker pressure

will not increase on the thicker pieces of stock.

Those skilled in this art will understand that the invention is not limited and restricted to the precise and exact details of construction illustrated and described since these may be modified within comparatively wide limits without departure from the substance and essence of the invention and without the sacrifice of any of its substantial benefits and advantages.

In the commercial employment of the invention, it is convenient and preferable to use a plurality, say ten or a dozen, of these individually responsive chip-breakers side 80 by side, whereby by their separate and independent yielding to the irregularities in the surface of the lumber, they may efficiently and effectively perform their chip-breaking functions.

I claim:

1. In a wood-working machine, the combination of a chip-breaker, a mounting therefor causing the chip-breaker to press against the work with increased effect the 90 thicker the work, and means to counteract said pressure increase.

2. In a wood-working machine, the combination of a chip-breaker, a mounting therefor causing the chip-breaker to press against the work with increased effect the thicker 95 the work, and spring means acting to press the chip-breaker toward the work with decreasing force as the thickness of the work increases.

3. In a wood-working machine, the combination of a chip-breaker adapted to bear on the work, a support, a pair of supporting members each pivotally connected to said support and to said chip-breaker, a coil 105 spring, and means connecting the opposite ends of said spring to said members on opposite sides of their pivotal connections with said support.

4. In a wood-working machine, the combination of a support, an upper lever fulcrumed intermediate its ends on said support, a lower link pivotally mounted on said support, a chip-breaker pivotally mounted on one arm of said lever and on the free end 115 of said link, a spring, means connecting one end of said spring with the other arm of said lever, and means connecting the opposite end of said spring with said link between its pivotal connections with the support and chip-breaker.

5. In a wood-working machine, the combination of a support, an upper bent lever fulcrumed intermediate its ends on said support, a lower link pivotally mounted on said support, a chip-breaker pivotally mounted on one arm of said lever and on the free end 125 of said link, a spring, means connecting one end of said spring with the other arm of said lever, and means connecting the oppo- 130

site end of said spring with said link between its pivotal connections with the support and chip-breaker.

6. In a wood-working machine, the combination of a support, an upper bent lever fulcrumed intermediate its ends on said support, a lower link pivotally connected at one end to said support, a chip-breaker pivotally mounted on the end of one arm of said lever and on the free end of said link, an eye-bolt pivotally connected to the other

arm of said lever, an adjustable stop nut on the shank of said eye-bolt, a hinge member pivotally connected to said link between its connections with said support and chip-breaker and having a stem, a guide-sleeve fitted on said stem and accommodating said shank, and a coil spring encircling said shank and guide sleeve and bearing at its opposite ends against said stop nut and 15 hinge member. 20

FRANKLIN L. LANE.
